[57] CLAIM

I claim the ornamental design for a lamp base, as shown and
described.

DESCRIPTION

FIG. 1 is a perspective view of the lamp base.
FIG. 2 is a front elevational view of the lamp base, the rear,
left side, and right side elevational views being identical.
FIG. 3 is a top plan view of the lamp base; and,
FIG. 4 is a bottom plan view of the lamp base.
Broken lines illustrate features or environmental compo-
nents that are not part of the design sought to be patented.
